UNITED STATES PATENT OFFICE.

CASWELL LEE LEONARD, OF CORINTH, MISSISSIPPI.

IRONING-BOARD.

1,282,091.

Specification of Letters Patent. Patented Oct. 22, 1918.

Application filed August 2, 1916. Serial No. 112,663.

To all whom it may concern:

Be it known that I, CASWELL LEE LEONARD, a citizen of the United States, residing at Corinth, in the county of Alcorn and State of Mississippi, have invented certain new and useful Improvements in Ironing-Boards, of which the following is a specification.

This invention aims to provide a novel

10 sad-iron shelf including a part which may be used as a hinge-pintle for an ironing board.

In the drawings:—Figure 1 shows in side elevation, an ironing board with which the 15 structure claimed has been assembled, parts appearing in section; Fig. 2 is a top plan of the ironing board detached from its support; Fig. 3 is an elevation of the sad-iron shelf.

20 The letter B marks a vertical support having a bracket G projecting therefrom. A sad-iron shelf is shown and includes a horizontal loop I', the ends of the loop being fashioned into contacting arms I and I² 25 disposed at right angles to the loop, and of unequal lengths, the longer arm I passing downwardly through the bracket G, and the shorter arm I² having its lower end face in contact with the bracket, thereby to space

30 the loop I' vertically from the bracket and to reduce the area of contact between the shelf and the bracket to a minimum, thus

avoiding an overheating of the bracket. Both of the arms I and I² are straight, whereby the loop I' may be disposed relatively close to the support B, to prevent a sad-iron from tilting backwardly between the loop and the support. The arm I may be used as a mounting for an ironing board C supported by a braced leg E and carrying 40 a sleeve board D.

I claim:—

The combination with a vertical support, of a bracket projecting therefrom; and a sad iron shelf in the form of a horizontal 45 loop, the ends of the loop being fashioned respectively into contacting arms of unequal lengths disposed at right angles to the loop, the longer arm passing downwardly through the bracket, and the shorter arm having its 50 lower end face in contact with the bracket, thereby to space the loop vertically from the bracket and to reduce the area of contact between the shelf and the bracket to a minimum, avoiding an overheating of the 55 bracket, both of the arms being straight, whereby the loop may be disposed relatively close to the support, to prevent a sad iron on the loop from tilting backwardly between the loop and the support.

CASWELL LEE LEONARD.
